UNITED STATES PATENT OFFICE.

THOMAS HASSALL HART, OF BIRMINGHAM, ENGLAND.

DEVICE FOR EJECTING BALLS FROM THE HOLES USED IN BALL-PUTTING GAMES.

Application filed August 6, 1928, Serial No. 297,771, and in Great Britain August 12, 1927.

This invention relates to ball putting and similar games, as played for example on lawns or a course of putting greens, in clock golf, and the like, in which the ball is played 5 into sunken pots or equivalent receptacles.

The object of the invention is to facilitate the extraction of balls from such pots or receptacles.

The invention comprises the combination 10 with the ball receiving pot or receptacle of a pivoted base adapted to be operated by the putting club, a walking stick, or otherwise, for ejecting the ball, without the stooping involved in the ordinary withdrawal by hand.

15 In the accompanying sheet of explanatory drawings:—

Figure 1 is a sectional view, Figure 2 a plan and Figure 3 an inverted plan, of a "putting" pot constructed in accordance with 20 this invention for use in golf practice, or clock golf or other like games.

In applying the invention as shown in connection with the putting pots or like ball receptacles to be sunk in a lawn or elsewhere 25 (as indicated by *a*, Figure 1) for golf ball putting, there is pivotally mounted within each of the tubular metal body parts *b*, ordinarily employed to form putting pots, a disc like or other suitably shaped base piece *c* 30 forming a platform or support for the ball. The said platform is so shaped and arranged relatively to its pivotal connection with the pot, that when the ball rolls into the latter the base is tilted and the ball as *d* brought to 35 rest at the lower side of same. In the example shown in the drawings, the base is attached to a diametrically arranged pivot spindle *e*. The dotted lines show the base tilted by the ball *d* which is also shown in 40 dotted lines. The extent to which the base can rock in either direction under the weight of the ball is limited by, for example, a cross piece *f* which serves as a support for the base.

Incidentally this cross piece has its terminal portions flanged and secured to the inner wall 45 of the receptacle so as to lie flush with the lower edge of the receptacle and thereby serve as a means for reinforcing the receptacle.

To eject the ball it is only necessary sharply 50 to depress the upper side of the inclined base, by means of the putting club or by a walking stick or otherwise, causing a corresponding sharp rise of the lower side of the platform, the ball being thereby thrown upward clear 55 of the pot.

The ejecting device may be varied in form and constructional details to meet varying services or requirements. Also if desired a hole may be formed in a convenient position 60 in the base *c* to permit the insertion into the ground of the usual flag post.

Having thus described my invention what I claim as new and desire to secure by Letters Patent is:—

1. In devices for ejecting balls from the holes used in ball putting games, the combination with a ball receiving receptacle, of a base pivoted transversely of the receptacle and adapted to rock in either direction, and 70 common means for limiting the rocking movement of the base and for reinforcing the receptacle.

2. In devices for ejecting balls from the holes used in ball putting games, the combination comprising a hollow cylindrical body open at both ends, a base pivoted on a diametrical axis substantially midway the height of the body, and a transverse support provided across the interior of the body beneath 80 the base so as to limit the rocking movement of the base in both directions and to reinforce the body, substantially as described.

In testimony whereof I have signed my name to this specification.

THOMAS HASSALL HART.
